INHALATION APPARATUS

Herbert Lehmann, Hampstead, London, England,
assignor to Riddell Products Limited, London,
England, a British company

Application December 13, 1939, Serial No. 309,089
In United Kingdom December 22, 1938

6 Claims. (Cl. 128—185)

This invention relates to inhalation apparatus and has particular reference to a type of inhaler comprising a hand bulb or other means for compressing air, leading to the jet or nozzle of a spray producer situated in a container for and adapted to spray inhaling medicaments, which container is in turn connected with a mouthpiece or mask adapted to be held close to the user's mouth and nose.

10 In this type of inhalation apparatus liquid is inserted into the container through an aperture or filling orifice in the well thereof and this aperture also serves as the requisite inlet for air which is required in addition to the air pumped in from the hand bulb or other source of pressure. When the apparatus is not in use this aperture has to be closed with a suitable cork or rubber stopper so as to prevent the escape of inhalation liquid. Moreover when the known type of apparatus is not in use the mask and its adjacent parts have 15 to be taken off and a plug or stopper inserted in the vapour outlet if escape of inhalation liquid is to be prevented when the apparatus is turned from the vertical position.

20 25 This aperture and stopper method is somewhat cumbersome and it is the object of this invention to provide an improved apparatus not suffering from this defect and having other advantages as will be seen from the following description.

30 It is a further object of this invention to provide fool-proof apparatus in which the filling orifice cannot be left open when the apparatus is in its non-operative position.

35 One particular example of the invention will now be described with reference to the accompanying drawing which is a cross-sectional view of the apparatus in its operative position.

In the apparatus illustrated the compressed air passes into the apparatus through a tube *a* coming either from the hand bulb or other source of supply. It passes through a cork or screw stopper *b* into the air jet *c* which is usually of glass with a fine outlet. This air jet *c* supports the liquid jet *d* by means of a branch support. The inhalation liquid is inserted into the container *e* and when the container is held upright in its operative position the liquid falls to the bottom as at *f*.

40 45 50 In the apparatus as at present known an aperture such as that shown in dotted lines at *g* is made in the container and this acts as an inlet through which the liquid *f* can be inserted and is also left open while the apparatus is in use. A downwardly depending sleeve *h* is supported from the top of the receptacle *e* and acts as a barrier

causing any air which enters at *g* to pass first downwardly around the outside of the sleeve *h* and then upwardly, passing past the jets of *c* and *d* and picking up the spray issuing therefrom.

In the apparatus as at present known a mask 5 such as *o* is removably carried by the receptacle *e* and is connected thereto by vapour passages. When the apparatus is not in use this mask is removed and the passage plugged by a stopper. In the improved apparatus constructed in accordance 10 with this invention, however, the head of the inhaler comprises a fixed outer sleeve *j* screwed to the top of the receptacle *e*. A rotatable inner hollow tube *k* fits within this sleeve *j* with a liquid tight joint and turns within it. 15 The tube *k* is centrally drilled with passage *n* leading to the inhalation mask *o*, the inner end of passage *n* being connected to the air or vapour passage *p* by a radially drilled passage *q*.

In this improved apparatus made in accordance 20 with this invention the aperture shown in dotted lines at *g* moreover does not exist but its place is taken by the filling orifice *r* which is formed in a cap screwed to the end of the tube *k* and turning therewith. The filling orifice leads to the hollow 25 centre *s* of the tube *k*.

The central passage *n* of the tube *k* is interrupted by a division *t* making the portion of the passage *s* separate from the passage *n*. A connecting passage *u* drilled radially runs parallel 30 with the passage *q* and connects the filling orifice *r* through passages *s* and *v* to the inside of the container *e* at a point outside the sleeve *h*.

In use the air passes up the tube *a* to the jet *c* thereby inducing liquid to pass up jet *d* and be 35 thereupon vaporized. The spray passes up the passage *p* and at the same time a partial vacuum is caused in the container *e* outside the sleeve *h*. Air is thereupon drawn in through the filling orifice *r* through passages *s*, *u* and *v* giving a 40 stream of air passing downwardly around the sleeve *h* and upwardly with the vapourized liquid. The air thus carrying vapour passes up passage *p* through passage *q* into passage *m* and out to 45 the user's mask *o*.

When it is desired to fill the apparatus this can be done easily through filling orifice *r*. When the apparatus is not in use the mask *o* is revolved preferably through half a revolution and thereupon passage *q* no longer coincides with passage *p* and passage *u* no longer coincides with passage *v* and thus a complete seal to the container *e* is obtained (except through the jet *e* which is so small as to be negligible) and the whole appa- 50 55

status becomes liquid-tight without the necessity for any stopper.

An advantage of this construction is that it immediately appears to the user whether the apparatus is open or not by looking at the position of the inhalation mask. Moreover if the apparatus is held in its normal upright position the user would not try to insert liquid when the holes *u* and *v* do not coincide since it is only when these 5 passages do coincide that the filling orifice points upwardly and is thus adapted to receive liquid.

It is preferable in the construction that the sleeve *h* is formed in one with the sleeve *j* or is fixed thereto.

15 15 In practice it may be found desirable to make the vapour passage leading from the top of the receptacle to the mask curve upwardly in the manner of a swan's neck.

I claim:

20 1. Inhalation apparatus comprising an air compressor, a jet of a spray producer, a conduit to lead the compressed air from the compressor to the jet, a container for the liquid to be sprayed, said container having a spray outlet and an orifice 25 additional thereto which serves both as a filling orifice and as an air inlet and common means for simultaneously closing both the spray outlet and the additional orifice when desired.

2. Inhalation apparatus comprising an air 30 compressor, a jet of a spray producer, a conduit to lead the compressed air from the compressor to the jet, a container for the liquid to be sprayed, said container having a spray outlet and an orifice additional thereto which serves both as a filling orifice and as an air inlet and interconnected means for simultaneously closing both the spray outlet and the additional orifice when desired.

3. Inhalation apparatus comprising an air

compressor, a jet of a spray producer, a conduit to lead the compressed air from the compressor to the jet, a container for the liquid to be sprayed, said container having a spray outlet and an orifice additional thereto which serves both as a filling orifice and as an air inlet and a common tap for simultaneously closing both the spray outlet and the additional orifice when desired.

4. Inhalation apparatus comprising an air compressor, a jet of a spray producer, a conduit 10 to lead the compressed air from the compressor to the jet, a container for the liquid to be sprayed, said container having a spray outlet and an orifice additional thereto which serves both as a filling orifice and as an air inlet and a spray 15 carrying tube rotatably mounted in the apparatus and provided with orifices so positioned that upon the tube being rotated to one of two alternative positions the spray outlet and the filling orifice are each open to the liquid receptacle 20 and upon the tube being rotated to the other of the alternative positions the spray outlet and the filling orifice are each sealed.

5. Inhalation apparatus as claimed in claim 4 in which an inhalation mask is so fixed to the 25 rotatable tube that upon the mask being in its operative position when held to the face of the user the spray outlet and the combined air inlet and filling orifice are each open to the liquid receptacle.

6. Inhalation apparatus as claimed in claim 4 in which the filling orifice is so positioned in the rotatable spray carrying tube that it is only upon the rotatable tube being turned to the position opening the filling orifice and the apparatus being held in the operative position that the filling orifice faces upwardly and allows gravity ingress of liquid.

30 35 HERBERT LEHMANN.
